BILLIARD TABLE OR THE LIKE

Robert I. Anderson, Spring Lake, and Robert C. Kelley, Muskegon, Mich., assignors to Brunswick Corporation, Chicago, Ill., a corporation of Delaware

Filed Oct. 14, 1965, Ser. No. 87,469

Term of patent 14 years

(Cl. D34—3)

FIG. 1 is a perspective view of a billiard table or the like embodying our new design, showing the top, one side and the right end thereof;

FIG. 2 is an elevational view showing the other side thereof;

FIG. 3 is an elevational view showing the other end thereof; and

FIG. 4 is a perspective view of a billiard table similar to that shown in FIG. 1 wherein the central support has been omitted.

The dominant features of the design are shown in full lines in the drawings.

We claim:

The ornamental design for a billiard table or the like, substantially as shown and described.
